[57] **CLAIM**

The ornamental design for a faucet spout, as shown and described.

DESCRIPTION

FIG. 1 is a front view of a faucet spout showing my new design;

FIG. 2 is a rear view thereof;

FIG. 3 is a left side view thereof, the right side view being a mirror image of the left side view;

FIG. 4 is a top view thereof;

FIG. 5 is a bottom view thereof;

FIG. 6 is a front view of a second embodiment of my new faucet spout;

FIG. 7 is a left side view thereof, the right side view being a mirror image of the left side view;

FIG. 8 is a rear view thereof;

FIG. 9 is a top view thereof; and

FIG. 10 is a bottom view thereof.
